UNITED STATES PATENT OFFICE

99,024

DESIGN FOR A GAME DEVICE

Charles Lee Hines, Council Bluffs, Iowa

Application December 27, 1935, Serial No. 60,310

Term of patent 14 years

To all whom it may concern:

Be it known that I, Charles Lee Hines, a citizen of the United States, residing at Council Bluffs, in the county of Pottawattamie and State of Iowa, have invented a new, original, and ornamental Design for a Game Device, of which the following is a specification, reference being had to the accompanying drawing, forming part thereof.

I claim:—

The ornamental design for a game device as shown.

CHARLES LEE HINES.
